UNITED STATES PATENT OFFICE.

CHARLES I. Dangler AND HENRY RUPPEL, OF CLEVELAND, OHIO, ASSIGNOR
TO THE Dangler STOVE AND MANUFACTURING COMPANY, OF SAME
PLACE.

HEAT-RADIATOR.

SPECIFICATION forming part of Letters Patent No. 516,920, dated March 20, 1894.

Application filed April 6, 1893. Serial No. 469,242. (No model.)

To all whom it may concern:

Be it known that we, CHARLES I. Dangler and HENRY RUPPEL, citizens of the United States, residing at Cleveland, in the county 5 of Cuyahoga and State of Ohio, have invented certain new and useful Improvements in Heat-Radiators; and we do hereby declare that the following is a full, clear, and exact description of the invention, which will enable others skilled in the art to which it appertains to make and use the same.

Our invention appertains to heat radiators of the variety in which gas is employed as an agent for heating, and the invention herein 15 shown and described is a modification of the radiator set forth and claimed in our application executed on the 27th day of March, 1893, and bearing Serial No. 469,241, filed April 6, 1893. In the construction shown here 20 a single burner tube is employed with a pair of circulating tubes, one upon each side thereof, and there are other differences of construction in view of said application, all substantially as shown and described herein and particularly pointed out in the claims.

In the accompanying drawings, Figure 1 is a vertical central sectional elevation of our modified form of radiator, taken on line 1, 1, Fig. 2, and Fig. 2 is a cross section thereof on 30 line 2, 2, Fig. 1. Fig. 3 is a vertical central sectional elevation at right angles to Fig. 1, and on a line corresponding to line 3, 3, Fig. 2. Fig. 4 is a perspective view of the combined burner and supporting frame for the induction or burner tube. Fig. 5 shows a modification of the induction tube in that it has a glass or transparent bulb or globe at its bottom about the burner, as hereinafter more fully described.

40 A represents the base of the burner, which, in this instance, is shown as made in a single piece and having seats *a* for the circulating tubes *B* and an air channel *a'*, space or chamber within said base beneath said tubes through which the heated air passes in its course out of the radiator. The tubes *B* are 45 surmounted by the cap or top *C* of the radiator, fashioned and ornamented about its edge as taste may dictate, and provided with seats 50 *c* for the tops of said tubes corresponding

substantially to the seats *a* for the lower ends thereof. This cap or top rises above said tubes some distance and is provided with suitable open-work plate or cover *D*, overlapping the cap *C* in this instance, though it may come 55 wholly within the same. Beneath this cover within the cap is supported a curved plate *E*, Figs. 1 and 3, resting along its edges upon the shoulders *c'* of the said cap, whereby it is held at such distance above the upper ends 60 of the tubes *B* that a free circulating air passage is provided beneath the plate from tube to tube.

Centrally between the two tubes *B*, *B*, and apart therefrom, is a burner tube *G*, suspended from a suitable seat on the cap *C*, and resting at its lower end upon burner frame *H*. This inner burner tube *G*, it will be seen, is shorter somewhat than the side tubes *B*, and preferably is made larger in cross section so 65 as to be capable of carrying a sufficient supply of air for both said tubes. The burner frame *H* is formed with a tubular ring *h*, having jets *h'* at intervals, and is connected at its center by cross tubes *h*² and with the gas 70 pipe *K* which passes up centrally through the base *A* and serves as a support for the said frame; short shouldered arms *h*³ are provided on frame *H* at intervals about its ring *h*, which serve as supports for the tube *G*, bearing 75 on the extremities of said arms. By this construction there is a free air circulation from beneath both within and without the burner ring. When the burner has been lighted a free circulation of air is at once established 80 upward in the tube *G* and downward in the side tubes *B*, *B*, and thence out through the openings *a'* in the front of the base *A*. It will thus be seen that the atmosphere which enters the tube *G* is not only 85 heated as it enters, but is carried forward through both sets of tubes and through the entire radiator, top and bottom. This long line of travel with the discharge at the bottom retards the flow of the air just enough to insure 90 good radiation, and in this respect differs very materially from a construction in which the burner is at the bottom of a tube and the discharge at the top thereof. In that case there is such free flow of air up through 95 100

the tube that radiation is greatly reduced and the heat is given off into the upper air of the room.

In Fig. 5 we show the burner tube G provided at its lower end with a transparent globe or bulb L, which serves to give out light as well as heat, and renders the radiator attractive as well as doubly useful. Any convenient way may be adopted for supporting the globe. In other respects this radiator is constructed substantially like the one shown in the remaining figures.

The openings α' may be as here shown or in other parts of the base, and the tubes B might be induction tubes and the central tube the return tube, thus reversing the order here shown; and the construction here shown might be otherwise modified and still be within the spirit of the invention. There might be one very large central induction tube and four return tubes, or the like.

Having thus described our invention, what we claim is—

1. The combined radiator and air heater herein described, comprising a chambered base, a chambered top, a central induction tube suspended from the top and having an open end separate from and above the base, a gas burner in said open end, and two hot air return flues connecting the top with the base, the said base having openings to discharge the heated air into the room, substantially as set forth.

2. The combined radiator and air heater herein described, comprising a base having openings in its edge through which the heated

air is discharged into the room, a chambered top, a number of tubes connecting the base and top and opening into both, an induction tube depending from the top and opening into it, and terminating in an open mouth above the base, and a burner arranged at the said open mouth to induce and heat a current of air which enters the chambered top through such induction tube and thence divides into the other tubes and descends them into the base whence it escapes into the room, substantially as set forth.

3. The combined radiator and air heater herein described, comprising a base having openings in its edge through which the heated air is discharged into the room, a chambered top, a number of tubes connecting the base and top and opening into both, an induction tube depending from the top and opening into it and terminating in an open mouth above the base, a curved plate arched over the tops of the several tubes within the chambered top, and a burner arranged at the said open mouth to induce and heat a current of air which enters the chambered top through such induction tube and thence divides into the other tubes and descends them into the base whence it escapes into the room, substantially as set forth.

Witness our hands to the foregoing specification this 27th day of March, 1893.

CHARLES I. Dangler.
HENRY RUPPEL.
